UNITED STATES PATENT OFFICE

158,622

COMBINED GOLF SWING AND LINE
INDICATOR

Ralph J. Sherwin, Toledo, Ohio

Application April 24, 1948, Serial No. 145,938

Term of patent 7 years

(Cl. D34—5)

To all whom it may concern:

Be it known that I, Ralph J. Sherwin, a citizen of the United States, residing at Toledo, in the county of Lucas and State of Ohio, have invented a new, original, and ornamental Design for Combined Golf Swing and Line Indicator, of which the following is a specification, reference being had to the accompanying drawing, forming part thereof.

Fig. 1 is a perspective view of a combined golf swing and line indicator, showing my new design; and

Fig. 2 is a side elevation of the same.

The dotted line showing of a ball resting on a tee inserted through the hole in the combined golf swing and line indicator of my design is for illustrative purposes only.

I claim:

The ornamental design for a combined golf swing and line indicator, as shown and described.

RALPH J. SHERWIN.
